US00D612827S

(12) **United States Design Patent**
Song et al.

(10) **Patent No.:** US D612,827 S
(45) **Date of Patent:** ** Mar. 30, 2010

(54) **MOBILE PHONE**

(75) Inventors: **Bong-Kyu Song**, Seoul (KR); **Joon-Suh Kim**, Anyang-Si (KR); **Chang-Hwan Hwang**, Goyang-Si (KR)

(73) Assignee: **Samsung Electronics Co., Ltd.**, Suwon-Si (KR)

(**) Term: **14 Years**

(21) Appl. No.: **29/333,263**

(22) Filed: **Mar. 5, 2009**

(30) **Foreign Application Priority Data**

Dec. 29, 2008 (KR) 30-2008-0055897

(51) **LOC (9) Cl.** **14-03**

(52) **U.S. Cl.** ..... **D14/138 AB**
